TWO-COLOR PRINTING PRESS

William R. Hildebrand, New York, N. Y.

Application June 27, 1941, Serial No. 399,985

7 Claims. (Cl. 101—186)

This invention relates to new and useful improvements in printing presses.

More specifically, the invention contemplates the construction of a one cylinder two color press. The invention proposes that the one cylinder be provided with the usual gripper mechanism, but which is operated to retain the sheet for a minimum of two revolutions, and proposes that the printing take place during these revolutions. With this arrangement the registration may be especially accurate because the gripper mechanism does not release the sheet during the two color printing operation.

Still further the invention proposes to characterize the two color press by providing it with a form holder reciprocally mounted on a frame beneath said cylinder mentioned in the previous paragraph which comprises the counter-pressure cylinder for the press, and it is proposed that the form holder be provided with two form sections with their leading edges spaced a distance preferably equal to the circumference of the counter-pressure cylinder. Furthermore, it is proposed to provide an ink supply means for each of the form sections arranged to individually ink the sections during the operation of the press.

Still further the invention contemplates mounting each of the ink supply means to move vertically and to have form rollers which in the lowered positions of the ink supply means contact said form sections.

Still further it is proposed to provide means for alternately raising and lowering said counter-pressure cylinder for periods of 2½ revolutions so that in its raised position the form sections may pass freely, and in its lowered positions it will engage the form sections when they pass.

Another object of the invention is to provide the press with means for moving said form holder in one direction for one stroke of its reciprocation while said counter-pressure cylinder is raised, and in the other direction for another stroke of its reciprocation while the counter-pressure cylinder is lowered.

It is also proposed to provide means for alternately raising and lowering said ink supply means so that in the lowered position of one of the ink supply means, one of said form sections will be inked once during each period of reciprocation of said form holder, and in the lowered position of the other of said ink supply means the other form section will be inked once during each period of reciprocation of said holder.

It is also contemplated to provide the press with means for operating said gripper means to

hold a sheet of paper on said counter-pressure cylinder for two revolutions thereof during a period that said counter-pressure cylinder is down to print said sheet with both of said form sections, and it is proposed that the start of the gripping operation be repeated once for every five revolutions of the counter-pressure drum. With this arrangement a particularly efficient two color press is obtained.

10 For further comprehension of the invention, and of the objects and advantages thereof, reference will be had to the appended claims in which the various novel features of the invention are more particularly set forth.

15 In the accompanying drawings forming a material part of this disclosure:

Fig. 1 is a side elevational view of a one cylinder two color press constructed in accordance with this invention.

20 Fig. 2 is a plan view of Fig. 1.

Fig. 3 is a transverse vertical sectional view taken on the line 3—3 of Fig. 1.

25 Fig. 4 is a fragmentary side elevational view similar to the central portion of Fig. 1 but illustrating the parts in a different position.

Figs. 5—13 inclusive are views similar to Fig. 4 but illustrating the parts in different positions so as to more clearly disclose the various phases of operation of the machine.

30 Fig. 14 is a fragmentary enlarged vertical sectional view taken on the line 14—14 of Fig. 3.

Fig. 15 is an elevational view of one of the cams of the machine, specifically the cam seen looking in the direction of the line 15—15 of Fig. 3.

35 Fig. 16 is an elevational view of another one of the cams of the machine, specifically the cam seen looking in the direction of the line 16—16 of Fig. 3.

The one cylinder two color press, in accordance 40 with this invention, includes a frame 20. A form holder 21 is reciprocally mounted on the frame 20 and has two form sections 22 and 23. A counter-pressure cylinder 24 is arranged above the form holder 21 and is indirectly supported on the frame 20 as will be hereinafter more fully described.

The counter-pressure cylinder 24 is provided with gripper means including the gripper fingers 25 (see Fig. 14) for engaging the lead edge of a sheet of material to be printed which, preferably, is of 45 a length equal to or less than half the circumference of said counter-pressure cylinder 24. A sheet of this type is schematically illustrated in Fig. 4 and other figures by reference letter S. The gripper means of the counter-pressure cylinder 24 is schematically indicated in Fig. 4 and in other 50 55

of the figures by reference letter G. The two form sections 22 and 23 have their lead edges 22^a and 23^a spaced a distance equal to the circumference of the counter-pressure cylinder 24.

The form holder 21 is provided with several flanges 26 which support rollers 27 engaging tracks 28 supported upon partition walls 29 mounted within the frame 20. The form holder 21 is also provided with a central downwardly extending bracket 30 which is fixedly mounted upon the holder 21 with fastening elements 31. This bracket 30 is provided with a plurality of rollers 32 mounted on its bottom portion and engaging another track 33 supported on the walls 29 of the frame 20. The counter-pressure cylinder 24 is mounted on a shaft 34 which has its ends rotatively mounted in slides 35 slidably mounted upon the side walls of the frame 20.

An ink supply means is provided for each of the form sections 22 and 23 and essentially comprise brackets 36 vertically slidably mounted in guide members 37 mounted on the frame 20. These brackets 36 support ink pads 38 which are associated with a plurality of furnishing rollers 39 cooperating with form rollers 40 which in the lowered positions of the ink supply means are adapted to contact the said form sections 22 and 23. In raised positions of the ink supply means, the form rollers 40 are sufficiently elevated so that the form sections 22 and 23 may pass without receiving ink.

Means is provided for alternately arising and lowering said counter-pressure cylinder 24 for periods of 2½ revolutions thereof, so that in its raised position the form sections 22 and 23 may pass freely beneath it, and in its lowered positions it will engage the form sections when they pass. This means is characterized by levers 41 which are pivotally mounted intermediate of their ends by pintles 42 supported on the frame 20.

The levers 41 are provided with slots 43 which are engaged by pins 44 mounted on the slides 35. The other ends of the levers 41 are provided with slots 45 which are engaged by pins 46 mounted on one of the ends of the levers 47. These levers 47 are pivotally mounted intermediate of their ends on a shaft 48 extending transversely across the frame 20. This shaft 48 is provided with a radial arm 47^a having a roller 49 which engages against a cam 50.

The cam 50 is fixedly mounted on a shaft 51 which is rotatively supported on the frame 20. The shaft 51 is provided with a sprocket 52 engaged by a driving chain or element 53 which engages over a sprocket 54 on a shaft 55 of a prime mover, such as an electric motor 56. The cam 50 has a low area 50^a extending substantially one-half of its circumference, and a high area 50^b extending the other half of its circumference. With this arrangement the counter-pressure cylinder 24 will be in a lowered position when the roller 49 engages the low area 50^a of the cam 50. The counter-pressure cylinder 24 will be in a raised position when the roller 49 engages the high area 50^b of the cam 50.

Means is provided for rotating said counter-pressure cylinder continuously in the same direction. This means includes a sprocket 58 mounted on the shaft 55 of the electric motor 56. An endless driving element 59 engages over a sprocket 58 and extends upwards and engages over a sprocket 60 mounted on a shaft 61 which extends transversely of the frame 20 and which is rotatively supported from projecting arms 35^a

of the slides 35. This shaft 61 is provided with gears 62 meshing with gears 63 rotatively supported on the slides 35. The gears 63 mesh with gears 64 on the ends of the shaft 55 which is rotatively supported on the slides 35.

The gears 64 mesh with gears 66 rotatively supported on the slides 35. The gears 66 mesh with gears 67 mounted upon the ends of the shaft 34 which supports the counter-pressure cylinder 24. The endless driving element 59 is engaged by an idler 68 which is mounted on an arm 69 pivotally supported by a pintle 70 mounted on the frame 20. A spring 71 acts between the frame 20 and the arm 69 for normally urging the idler 68 to tension the endless drive member 59. The arrangement is such that rotation of the motor 56 indirectly rotates the counter-pressure cylinder 24 continuously in a counter-clockwise direction in relation to Fig. 4 and similar other figures.

Means is provided for moving the form holder 21 in one direction for one stroke of its reciprocation, while said counter-pressure cylinder 24 is raised, and in the other direction for another stroke of its reciprocation while said counter pressure cylinder 24 is lowered. This means is characterized by opposed racks 73 and 74 mounted upon the top and bottom edge portions of a longitudinal opening 75 formed in the bracket 30. A gear 76 is mounted on the shaft 65. This shaft 65 passes through slots 77 formed in the walls of the frame 20 so as not to interfere with upward and downward motion of the slides 35. In the normal position of the slides 35, the gear 76 engages the top rack 73. In lowered positions of the slides 35, the gear 76 engages the bottom rack 74.

Since the shaft 65 is contained in the drive train of the counter-pressure cylinder 24 it will always rotate in the same direction. However, the form holder 21 will be driven in one direction, or the other, depending upon whether the gear 76 is in mesh with the rack 73, or whether the gear 76 is in mesh with the rack 74.

It should be noted that when the slides 35 are in their raised positions, the counter-pressure cylinder 24 will be in its raised position. In this position of the cylinder 24, the gear 76 engages the top rack 73, and consequently the form holder 21 will be driven in one direction. Similarly, when the counter-pressure cylinder 24 is in its lowered position, the gear 76 will engage the bottom rack 74 to drive the form holder in the opposite direction.

Means is provided for alternately raising and lowering the said ink supply means so that in the lowered position one of said form sections 22 or 23 will be inked once during each period of reciprocation of the form holder 21, and in the lowered position of the other of said ink supply means, the other form section will be inked once during each period of reciprocation of said form holders.

The means for raising and lowering the ink supply means illustrated to the left of the counter-pressure cylinder 24, as illustrated in Fig. 4, includes a rod 80 connected with the bracket 36 and extending downwards and pivotally connected with one arm of a bell crank 81 which is pivotally supported intermediate of its ends by a pintle 82. A link 83 connects the other arm of the bell crank 81 with a point eccentric on a disc 84 which is turnably supported concentrically by a pintle 85 mounted on the frame 20. The ink supply means to the right of the counter-pres-

sure cylinder 24 has its bracket 36 supported by a rod 86 which extends downwards and pivotally connects with a bell crank 87 which is pivotally supported intermediate of its ends by a pintle 88 mounted on the frame 20. The other end of the bell crank 87 pivotally connects with a link 89 which is pivotally connected eccentrically on the disc 84.

A pair of upwardly and forwardly inclined arms 90 are pivotally mounted at their bottom ends by pintles 91 on the frame 20. Another pair of parallel arms 92 is pivotally connected with the parallel arms 90 to form a parallelogram of arms. One of the arms 92 has a projecting end portion 92^a which is provided with a roller 93 engaging against a cam 94. This cam 94 is mounted on the shaft 51. A spring 95 is connected with one of the levers 90 and with the frame 20 for normally urging the parallelogram of arms in a direction that causes the roller 93 to engage the cam 94. A link 96 has one of its ends pivotally connected with one of the arms 92 and its other end pivotally connected eccentric of the disc 84.

The cam 94 has a low area 94^a for substantially one-half of its periphery and a high area 94^b for the remaining half of its periphery. The arrangement is such that when the roller 93 engages the high area 94^b the parts will be in the positions as illustrated in Fig. 4 in which the ink supply means to the left of the counter-pressure cylinder 24 in its raised position and the ink supply means to the right of the counter-pressure cylinder is in its lowered position. When the roller 93 engages the low area 94^a of the cam 94, for example, as shown in Fig. 3, the ink supply means to the left of the counter-pressure cylinder 24 will be in its lowered position and the ink supply means to the right of the counter-pressure cylinder 24 will be in its raised position. When the high portion 94^b engages the roller 93 the parallelogram of arms will be forced downwards so that the disc 84 is turned slightly clockwise. When the roller 93 engages the low portion 94^a of the cam, the spring 95 will move the parallelogram of arms upwards and slightly to the left so that the disc 84 is turned counter-clockwise to reverse the positions of the ink supply means.

Means is also provided for operating the gripper means of the counter-pressure cylinder 24 which is characterized by the gripper fingers 25 (see Fig. 14). This means is arranged to hold a sheet of paper on the counter-pressure cylinder 24 for two revolutions thereof during the period that said counter-pressure cylinder is down to print said sheet with both of said form sections 22 and 23, and the start of the gripping operation repeating once for each five revolutions of the counter-pressure cylinder 24. The gripping means is of conventional design except for the way in which it is caused to open and close. The gripping means characterized by a recess 100 formed in the cylinder 24 in which the usual brackets 101 are mounted which support the usual shaft 102 upon which the gripping fingers 25 are mounted.

Resilient means 103 act to normally urge the gripping fingers 25 into their closed positions. One end of the shaft 102 extends from the end of the cylinder 24. A finger 105 (see Figs. 3 and 14) is mounted on this projecting end of the shaft 102. This finger 105 controls the opening of the gripping fingers 25. A mechanism is provided to operate the fingers 25. This mechanism includes a lever 106 pivotally mounted at its bot-

tom end by a pintle 107 upon the adjacent slide 35. The lever 106 is urged towards the fingers 105 by an expansion spring 108 mounted between the lever 106 and the slide 35. The lever 106 is held laterally in an inoperative position by the following mechanism.

A pin 109 engages a slot 110 formed in a bracket attached on the lever 106. The pin 109 is mounted upon a slidably mounted rod 111 which extends downwards along one of the walls of the frame 20.

The rod 111 has a laterally offset middle section 111^a. The bottom end of the rod 111 is provided with a roller 112 which engages a cam 113, see Figs. 3 and 15, which is mounted on the shaft 51. This cam 113 has two low spots 113^a set at positions from each other representing two rotations of the cylinder 24. The arrangement is such that when the roller 112 reaches a low spot 113^a, the spring 108 will move the lever 106 towards the end of the cylinder 24. Then the tail end of the finger 105 will engage the lever 106, see Fig. 14, to pivot open the gripper fingers 25. This is the condition of the parts shown in Fig. 4. An ejecting pin 115 is provided for each gripper finger 25. These pins are urged inwards by springs 116. The pins 115 are urged outwards by projections 117 on the hubs of the gripper fingers 25 engaging the inner ends of the pins 115. The arrangement is such that when the gripper fingers are opened the pins 115 extend upwards.

Means is provided for forcing the lead end of the sheets into a position in which the gripper fingers 25 may grip the same. This means is characterized by pusher fingers 120. These pusher fingers are mounted on a rod 121 which is journaled on standards 122 mounted on the frame 20. A radial arm 123 projects from the rod 121 and is pivotally connected with a rod 124 which slidably engages through a bearing 125 mounted on the frame 20. The rod 124 is also provided with a laterally offset middle portion 124^a similar to the rod 111. The bottom end of the rod 124 is provided with a roller 126 which engages a cam 127 (see Figs. 3 and 15). This cam 127 is mounted on a shaft 128 provided with a pinion 129 meshing with a pinion 130 on a shaft 131 rotatively supported. This shaft 131 is provided with another pinion 132 meshing with a pinion 133 mounted on the shaft 51.

The arrangement is such that rotations of the shaft 51 indirectly rotate the cam 127 in synchronization with the cam 94. The cam 127 has one high spot 127^a which forces the roller 126 upwards to move the rod 124 upwards which pivots the rod 121 causing the pusher fingers 120 to push the lead edge of a sheet of paper downwards for the gripper fingers 25 to catch.

The press, in accordance with this invention, is also provided with the usual accessories associated with presses. For example, Figs. 1 and 2 illustrate the usual means for supplying the press with sheets of paper. There is the usual holder 135 for a stack of sheets of paper and the usual mechanism 136 for feeding one sheet at a time to the usual conveyor 137 which moves the sheet forwards to a position in which its lead edge may be engaged by the gripper means of the counter-pressure cylinder 24. The press is also provided with a take-off conveyor 138 arranged to catch the lead edge of a discharged sheet and carry the sheet along to a stacking table 139. The details of these mechanisms will not be given in this specification as they form no part of the invention. The press may also be provided with the

customary ink drying means and other devices associated with presses.

The operation of the press may be best understood by examining Figs. 4-13 inclusive which clearly illustrate the cycle of operation. Starting with Fig. 4 it should be noted that the sheet S is moving towards the counter-pressure cylinder 24 into a position in which the gripper means G of the counter-pressure cylinder will grip the lead edge of the sheet. At this moment the printing forms 22 and 23 are to the left of the cylinder 24.

The gripper means G is at the top. The cylinder 24 is in a raised position, indicated by the adjacent arrow, and the inking means is arranged so that one is up and one is down as indicated by their respective arrows. The printing form 23 at this moment is already inked since it previously passed the inking means at the right which is down. This may be understood from the subsequent description of the operation. The form holder 21 is in a position near its extreme left hand end. The next instant the lead edge of the sheet S is gripped.

Fig. 5 illustrates the position of the various parts with the counter-pressure cylinder 24 turned $\frac{1}{4}$ of a revolution from the position shown in Fig. 4. Note the gripper point G. The sheet S is now being carried around by the cylinder 24. The form holder 21 is now in its extreme left position and already to start moving towards the right. The cylinder 24 is still raised and the inking means is still in a position as shown in Fig. 4. The next instant the roller 49 engages the start of the low area 50^a of the cam 50. This indirectly causes the slides 35 to move downwards so that the counter-pressure cylinder 24 is now in its lowered position. This engages the gear 76 against the bottom rack 74 and a $\frac{1}{4}$ of a revolution later of the cylinder 24, the parts will be in the position illustrated in Fig. 6.

In Fig. 6 the cylinder 24 is now in its half a revolution position. Note the gripper point G. The lead sheet is now aligned with the lead edge of the printing form 23. The inking means are still in the same positions in which they were during Figs. 4 and 5. The first color is now being printed.

Fig. 7 illustrates the position of the parts one-half revolution later which represents a complete revolution of the cylinder 24. Note the gripper point G. At this point of operation the roller 93 engages the low portion of the cam 94 which causes the inking means to reverse, that is, the inking means to the left of the cylinder 24 is now down and the other means to the right of the cylinder 24 is now up. The inking means now to the left, engages the printing form 22, inking same. The form holder 21 is still traveling towards the right.

Fig. 8 illustrates the relative positions of the parts one-half revolution later, which represents $\frac{1}{2}$ revolutions of the cylinder 24 from its starting position. Note the position of gripper point G. In Fig. 8 the sheet S is now in a position where its lead edge aligns with the lead edge of the form section 22 which has just been inked. The form holder 21 is still traveling towards the right.

Fig. 9 represents the parts one-half revolution of the cylinder 24 later from the position shown in Fig. 8. Note gripper point G. This represents two complete revolutions of the cylinder 24. At this point of the operation the sheet S has been printed twice, once by the form 23 and once by the form 22. Attention is called to the fact that the ink means to the right of the cylinder 24

is up so that form 22 may pass it without receiving ink. At this point the roller 112 rides into a low spot 113^a of the cam 113 which causes the lever 106 to move towards the finger 105. This 5 indirectly opens the gripper fingers 25 and the pins 115 eject the lead edge of the sheet which is then caught by the take-off conveyor system.

Three-quarters of a revolution later, note gripper point G, the parts are in the positions illustrated in Fig. 10 which represents $2\frac{3}{4}$ rotations of the cylinder 24 from its starting position. At this point the form holder 21 is in its extreme right position. The roller 49 rides up on the high portion 50^b of the cam 50 which indirectly 15 causes the cylinder 24 to move upwards. This causes the gear 76 to engage with the bottom rack 74. The form holder will now move towards the left. The sheet S at this moment has been completely discharged from the press, as indicated in Fig. 10. One-quarter of a revolution later, the parts will be in the position shown in Fig. 11, note gripper point G, which represents three revolutions of the cylinder 24. At this 20 moment the inking means is still in the same position in which it was in Fig. 10.

The ink supply means to the left of the counter-pressure cylinder 24 is still down and the ink supply means to the right of the counter-pressure cylinder 24 is still up. The form section 22 is beneath the ink supply means at the right but will receive no ink. A short time later the form section 22 will be to the left of the ink supply means which is at the right, and then the ink supply means will reverse in position. 30 The roller 93 rides upon the high portion 94^b of the cam 94 causing the ink supply means at the right to move down and the ink supply at the left to move up.

One revolution later the parts will be as shown 40 in Fig. 12, which represents four revolutions of the counter-pressure cylinder 24. It should be noted that the ink supply means at the right is now down and inking the form section 23. The ink supply means to the left is in its raised position so that the form section 22 may 45 pass freely. One revolution later the parts will be in the positions shown in Fig. 5, which represents five complete revolutions of the counter-pressure cylinder 24. This view is identical to the view shown in Fig. 4. A new sheet S is now 50 in position at the top of the counter-pressure cylinder 24 and the operation is ready to repeat.

While I have illustrated and described the 55 preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a one cylinder two color press, a frame, 65 a counter pressure cylinder for said press having gripper means for engaging the lead edge of a sheet to be printed which is of a length equal to or less than one half the circumference of said counterpressure cylinder, a form holder reciprocally mounted on said frame and beneath said counterpressure cylinder and having two form sections with their leading edges spaced a distance equal to the circumference of said counterpressure cylinder, an ink supply means for each of said form sections and vertically

slidably mounted and having form rollers which in the lowered positions of said ink supply means contact said form sections, means for alternately raising and lowering said counter-pressure cylinder for periods of two and one half revolutions so that in its raised position the form sections may pass freely and in its lowered position it will engage the form sections when they pass, means for rotating said counter-pressure cylinder continuously in the same direction, means for moving said form holder in one direction for one stroke of its reciprocation while said counterpressure cylinder is raised and in the other direction for another stroke of its reciprocation while said counterpressure cylinder is lowered, means for alternately raising and lowering said ink supply means so that in the lowered position of one of said ink supply means one of said form sections will be inked once during each period of reciprocation of said form holder, and in the lowered position of the other of said ink supply means the other form section will be inked once during each period of reciprocation of said form holder, and means for operating said gripper means to hold a sheet of paper on said counterpressure cylinder for two revolutions thereof during a period that said counter-pressure cylinder is down to print said sheet with both of said form sections and the start of the gripping operation repeating once for each five revolutions of said counterpressure cylinder, said means for alternately raising and lowering said counterpressure cylinder comprising slides vertically supported on said frame and supporting said cylinder, and means for raising and lowering said slides controlled with a cam, said cam having a high spot for one half of its circumference and a low spot for the other half and cooperative with a roller on a pivotally mounted lever connected with a linkage system, in turn connected with said slides, said linkage system being arranged on the sides of said frame, and said slides being also arranged on the sides of the frame.

2. In a one cylinder two color press, a frame, a counterpressure cylinder for said press having gripper means for engaging the lead edge of a sheet to be printed which is of a length equal to or less than one half the circumference of said counterpressure cylinder, a form holder reciprocally mounted on said frame and beneath said counterpressure cylinder and having two form sections with their leading edges spaced a distance equal to the circumference of said counterpressure cylinder, an ink supply means for each of said form sections and vertically slidably mounted and having form rollers which in the lowered positions of said ink supply means contact said form sections, means for alternately raising and lowering said counterpressure cylinder for periods of two and one half revolutions so that in its raised position the form sections may pass freely and in its lowered position it will engage the form sections when they pass, means for rotating said counterpressure cylinder continuously in the same direction, means for moving said form holder in one direction for one stroke of its reciprocation while said counterpressure cylinder is raised and in the other direction for another stroke of its reciprocation while said counterpressure cylinder is lowered, means for alternately raising and lowering said ink supply means so that in the lowered position of one of said ink supply means one of said form sections will be inked once during each period of reciprocation of said form holder, and in the lowered position of the other of said ink supply means the other form section will be inked once during each period of reciprocation of said form holder, and means for operating said gripper means to hold a sheet of paper on said counterpressure cylinder for two revolutions thereof during a period that said counterpressure cylinder is down to print said sheet with both of said form sections and the start of the gripping operation repeating once for each five revolutions of said counterpressure cylinder, said means for rotating said counterpressure cylinder comprises a prime mover having a pulley engaged by an endless driving element engaged with a pulley mounted on said slide, and an idler mechanism for maintaining the tension of said endless member, said slide being provided with a train of gears for communicating the rotations.

3. In a one cylinder two color press, a frame, a counterpressure cylinder for said press having gripper means for engaging the lead edge of a sheet to be printed which is of a length equal to or less than one half the circumference of said counterpressure cylinder, a form holder reciprocally mounted on said frame and beneath said counterpressure cylinder and having two form sections with their leading edges spaced a distance equal to the circumference of said counterpressure cylinder, an ink supply means for each of said form sections and vertically slidably mounted and having form rollers which in the lowered positions of said ink supply means contact said form sections, a slide supporting said counterpressure cylinder, means for alternately raising and lowering said slide to correspondingly raise and lower said counterpressure cylinder for periods of two and one half revolutions so that in its raised position the form sections may pass freely and in its lowered position it will engage the form sections when they pass, means for rotating said counterpressure cylinder continuously in the same direction, means for moving said form holder in one direction for one stroke of its reciprocation while said counterpressure cylinder is raised and in the other direction for another stroke of its reciprocation while said counterpressure cylinder is lowered, means for alternately raising and lowering said ink supply means so that in the lowered position of one of said ink supply means one of said form sections will be inked once during each period of reciprocation of said form holder, and in the lowered position of the other of said ink supply means the other form section will be inked once during each period of reciprocation of said form holder, and means for operating said gripper means to hold a sheet of paper on said counterpressure cylinder for two revolutions thereof during a period that said counterpressure cylinder is down to print said sheet with both of said form sections and the start of the gripping operation repeating once for each five revolutions of said counterpressure cylinder, said means for rotating said counterpressure cylinder comprises a prime mover having a pulley engaged by an endless driving element engaged with a pulley mounted on said slide, and an idler mechanism for maintaining the tension of said endless member.

4. In a one cylinder two color press, a frame, a counterpressure cylinder for said press having gripper means for engaging the lead edge of a sheet to be printed which is of a length equal to or less than one half the circumference of said counterpressure cylinder, a form holder reciprocally mounted on said frame and beneath said counterpressure cylinder and having two form sections with their leading edges spaced a distance equal to the circumference of said counterpressure cylinder, an ink supply means for each of said form sections and vertically slidably mounted and having form rollers which in the lowered positions of said ink supply means contact said form sections, a slide supporting said counterpressure cylinder, means for alternately raising and lowering said slide to correspondingly raise and lower said counterpressure cylinder for periods of two and one half revolutions so that in its raised position the form sections may pass freely and in its lowered position it will engage the form sections when they pass, means for rotating said counterpressure cylinder continuously in the same direction, means for moving said form holder in one direction for one stroke of its reciprocation while said counterpressure cylinder is raised and in the other direction for another stroke of its reciprocation while said counterpressure cylinder is lowered, means for alternately raising and lowering said ink supply means so that in the lowered position of one of said ink supply means one of said form sections will be inked once during each period of reciprocation of said form holder, and in the lowered position of the other of said ink supply means the other form section will be inked once during each period of reciprocation of said form holder, and means for operating said gripper means to hold a sheet of paper on said counterpressure cylinder for two revolutions thereof during a period that said counterpressure cylinder is down to print said sheet with both of said form sections and the start of the gripping operation repeating once for each five revolutions of said counterpressure cylinder, said means for rotating said counterpressure cylinder comprises a prime mover having a pulley engaged by an endless driving element engaged with a pulley mounted on said slide, and an idler mechanism for maintaining the tension of said endless member, said slide being provided with a train of gears for communicating the rotations.

to or less than one half the circumference of said counterpressure cylinder, a form holder reciprocally mounted on said frame and beneath said counterpressure cylinder and having two form sections with their leading edges spaced a distance equal to the circumference of said counterpressure cylinder, an ink supply means for each of said form sections and vertically slidably mounted and having form rollers which in the lowered positions of said ink supply means contact said form sections, a slide supporting said counterpressure cylinder, means for alternately raising and lowering said slide to correspondingly raise and lower said counterpressure cylinder for periods of two and one half revolutions so that in its raised position the form sections may pass freely and in its lowered position it will engage the form sections when they pass, means for rotating said counterpressure cylinder continuously in the same direction, means for moving said form holder in one direction for one stroke of its reciprocation while said counterpressure cylinder is raised and in the other direction for another stroke of its reciprocation while said counterpressure cylinder is lowered, means for alternately raising and lowering said ink supply means so that in the lowered position of one of said ink supply means one of said form sections will be inked once during each period of reciprocation of said form holder, and in the lowered position of the other of said ink supply means the other form section will be inked once during each period of reciprocation of said form holder, and in the lowered position of the other of said ink supply means the other form section will be inked once during each period of reciprocation of said form holder, and means for operating said gripper means to hold a sheet of paper on said counterpressure cylinder for two revolutions thereof during a period that said counterpressure cylinder is down to print said sheet with both of said form sections and the start of the gripping operation repeating once for each five revolutions of said counterpressure cylinder, said means for rotating said counterpressure cylinder comprises a prime mover having a pulley engaged by an endless driving element engaged with a pulley mounted on said slide, and an idler mechanism for maintaining the tension of said endless member, said slide being provided with a train of gears for communicating the rotations, and said means for moving said form holder comprising a gear connected with said train of gears and meshing with a top rack mounted on said form holder, and in a lowered position of the slide and counterpressure cylinder meshing with a bottom rack also mounted on said form holder.

5. In a one cylinder two color press, a frame, a counterpressure cylinder for said press having gripper means for engaging the lead edge of a sheet to be printed which is of a length equal to or less than one half the circumference of said counterpressure cylinder, a form holder reciprocally mounted on said frame and beneath said counterpressure cylinder and having two form sections with their leading edges spaced a distance equal to the circumference of said counterpressure cylinder, an ink supply means for each of said form sections and vertically slidably mounted and having form rollers which in the lowered position of said ink supply means contact said form sections, a slide supporting said counterpressure cylinder, means for alternately raising and lowering said slide to correspondingly raise and lower said counterpressure cylinder for periods of two and one half revolutions so that in its raised position the form sections may pass freely and in its lowered position it will engage the form sections when they pass, means for rotating said counterpressure cylinder continuously in the same direction, means for moving said form holder in one direction for one stroke of its reciprocation while said counterpressure cylinder is raised and in the other direction for another stroke of its reciprocation while said counterpressure cylinder is lowered, means for alternately raising and lowering said ink supply means so that in the lowered position of one of said ink supply means one of said form sections will be inked once during each period of reciprocation of said form holder, and

lowered position it will engage the form sections when they pass, means for rotating said counterpressure cylinder continuously in the same direction, means for moving said form holder in one direction for one stroke of its reciprocation while said counterpressure cylinder is raised and in the other direction for another stroke of its reciprocation while said counterpressure cylinder is lowered, means for alternately raising and lowering said ink supply means so that in the lowered position of one of said ink supply means one of said form sections will be inked once during each period of reciprocation of said form holder, and in the lowered position of the other of said ink supply means the other form section will be inked once during each period of reciprocation of said form holder, and means for operating said gripper means to hold a sheet of paper on said counterpressure cylinder for two revolutions thereof during a period that said counterpressure cylinder is down to print said sheet with both of said form sections and the start of the gripping operation repeating once for each five revolutions of said counterpressure cylinder, said means for rotating said counterpressure cylinder comprises a prime mover having a pulley engaged by an endless driving element engaged with a pulley mounted on said slide, and an idler mechanism for maintaining the tension of said endless member, said slide being provided with a train of gears for communicating the rotations, and said means for moving said form holder comprising a gear connected with said train of gears and meshing with a top rack mounted on said form holder, and in a lowered position of the slide and counterpressure cylinder meshing with a bottom rack also mounted on said form holder, said means for alternately raising and lowering said ink supply means comprising rods connected with the ink supply means and connected with pivotally mounted bell cranks which are connected by links eccentrically on a control disc, and means for turning said disc.

6. In a one cylinder two color press, a frame, a counterpressure cylinder for said press having gripper means for engaging the lead edge of a sheet to be printed which is of a length equal to or less than one half the circumference of said counterpressure cylinder, a form holder reciprocally mounted on said frame and beneath said counterpressure cylinder and having two form sections with their leading edges spaced a distance equal to the circumference of said counterpressure cylinder, an ink supply means for each of said form sections and vertically slidably mounted and having form rollers which in the lowered positions of said ink supply means contact said form sections, a slide supporting said counterpressure cylinder, means for alternately raising and lowering said slide to correspondingly raise and lower said counterpressure cylinder for periods of two and one half revolutions so that in its raised position the form sections may pass freely and in its lowered position it will engage the form sections when they pass, means for rotating said counterpressure cylinder continuously in the same direction, means for moving said form holder in one direction for one stroke of its reciprocation while said counterpressure cylinder is raised and in the other direction for another stroke of its reciprocation while said counterpressure cylinder is lowered, means for alternately raising and lowering said ink supply means so that in the lowered position of one of said ink supply means one of said form sections will be inked once during each period of reciprocation of said form holder, and

in the lowered position of the other of said ink supply means the other form section will be inked once during each period of reciprocation of said form holder, and means for operating said gripper means to hold a sheet of paper on said counterpressure cylinder for two revolutions thereof during a period that said counterpressure cylinder is down to print said sheet with both of said form sections and the start of the gripping operation repeating once for each five revolutions of said counterpressure cylinder, said means for rotating said counterpressure cylinder comprises a prime mover having a pulley engaged by an endless driving element engaged with a pulley mounted on said slide, and an idler mechanism for maintaining the tension of said endless member, said slide being provided with a train of gears for communicating the rotations, and said means for moving said form holder comprising a gear connected with said train of gears and meshing with a top rack mounted on said form holder, and in a lowered position of the slide and counterpressure cylinder meshing with a bottom rack also mounted on said form holder, said means for alternately raising and lowering said ink supply means comprising rods connected with the ink supply means and connected with pivotally mounted bell cranks which are connected by links eccentrically on a control disc, and means for turning said disc, comprising a link eccentrically on the disc and connected with a parallelogram of arms provided with a roller engaging a control cam.

7. In a one cylinder two color press, a frame, a counterpressure cylinder for said press having gripper means for engaging the lead edge of a sheet to be printed which is of a length equal to or less than one half the circumference of said counterpressure cylinder, a form holder reciprocally mounted on said frame and beneath said counterpressure cylinder and having two form sections with their leading edges spaced a distance equal to the circumference of said counterpressure cylinder, an ink supply means for each of said form sections and vertically slidably mounted and having form rollers which in the lowered positions of said ink supply means contact said form sections, a slide supporting said counterpressure cylinder, means for alternately raising and lowering said slide to correspondingly raise and lower said counterpressure cylinder for

periods of two and one half revolutions so that in its raised position the form sections may pass freely and in its lowered position it will engage the form sections when they pass, means for rotating said counterpressure cylinder continuously in the same direction, means for moving said form holder in one direction for one stroke of its reciprocation while said counterpressure cylinder is raised and in the other direction for another stroke of its reciprocation while said counterpressure cylinder is lowered, means for alternately raising and lowering said ink supply means so that in the lowered position of one of said ink supply means one of said form sections will be inked once during each period of reciprocation of said form holder, and in the lowered position of the other of said ink supply means the other form section will be inked once during each period of reciprocation of said form holder, and means for operating said gripper means to hold a sheet of paper on said counterpressure cylinder for two revolutions thereof during a period that said counterpressure cylinder is down to print said sheet with both of said form sections and the start of the gripping operation repeating once for each five revolutions of said counterpressure cylinder, said means for rotating said counterpressure cylinder comprises a prime mover having a pulley engaged by an endless driving element engaged with a pulley mounted on said slide, and an idler mechanism for maintaining the tension of said endless member, said slide being provided with a train of gears for communicating the rotations, and said means for moving said form holder comprising a gear connected with said train of gears and meshing with a top rack mounted on said form holder, and in a lowered position of the slide and counterpressure cylinder meshing with a bottom rack also mounted on said form holder, said means for alternately raising and lowering said ink supply means comprising rods connected with the ink supply means and connected with pivotally mounted bell cranks which are connected by links eccentrically on a control disc, and means for turning said disc, comprising a link eccentrically on the disc and connected with a parallelogram of arms provided with a roller engaging a control cam, said cam having a low area for half of its circumference and a high area for the other half.

50 WILLIAM R. HILDEBRAND.
